(57) **CLAIM**

The ornamental design for a toy brick with an upstanding knob as shown and described.

DESCRIPTION

FIG. 1 is a back perspective view of a toy brick with an upstanding knob.

FIG. 2 is a front plan view of the toy brick with an upstanding knob.

FIG. 3 is a back plan view of the toy brick with an upstanding knob.

FIG. 4 is a first side plan view of the toy brick with an upstanding knob.

FIG. 5 is a second side plan view of the toy brick with an upstanding knob.

FIG. 6 is top plan view of the toy brick with an upstanding knob.

FIG. 7 is a bottom view of the toy brick with an upstanding knob.

FIG. 8 is a bottom perspective view of the toy brick with an upstanding knob; and,

FIG. 9 is a front perspective view of the toy brick with an upstanding knob.

The broken lines in the figures show features of the toy brick with an upstanding knob that form no part of the claimed design.

1 Claim, 9 Drawing Sheets
